Atty

UNITED STATES PATENT OFFICE.

JOSEPH R. BROWN, OF PROVIDENCE, ASSIGNOR OF TWO-THIRDS TO HENRY A. STEARNS, OF LINCOLN, RHODE ISLAND, AND JOHN M. HALL, OF WADINGFORD, CONNECTICUT.

AUTOMATIC FIRE-EXTINGUISHER.

SPECIFICATION forming part of Letters Patent No. 245,916, dated August 16, 1881.

Application filed April 29, 1889. (No model.)

To all whom it may concern:

Be it known that I, JOSEPH R. BROWN, of Providence, county of Providence, and State of Rhode Island, have invented a new and useful

- 5 Improvement in Automatic Fire-Extinguishers; and I hereby declare that the following is a full, clear, and exact description of the same, reference being had to the accompanying drawings, forming part of this specification.
- 10 The object of this invention is to construct an automatic device that shall be released by the heat of a fire and spread the water in thin sheets over an extended surface.

The invention consists in the peculiar construction of the distributor and the peculiar arrangement of a check-valve, by means of which the water is kept from contact with the soldered joint, and thus the reliability of the device is increased.

- 15 Figure 1 is a side elevation of my improved automatic fire-extinguisher. Fig. 2 is a sectional view of the same, and Fig. 3 is a top view of the same. Fig. 4 is a side elevation view, and Fig. 5 a section of a modification of 25 my improved automatic fire-extinguisher.

In the drawings, *a* represents a branch pipe connecting with the water-supply pipe of a system of pipes distributed through a building, and connected with a water-supply for extinguishing fires.

- 30 *b* is an elbow.
- c* represents a check-valve. The object of this check-valve is to separate the air from the water, so as to prevent the absorption of the 35 air by the water. When the system of pipes is being filled with water the air is driven before it to the extremities of the pipes, where the automatic distributors are placed, and the check-valve *c* will be raised by the pressure of 40 the air, and the air will pass by the valve, and at each pulsation or sudden increase of pressure the valve will allow air to pass by, but will not allow the air to return or come in contact with the water. The pressure of confined air 45 above the valve will thus equal the maximum

pressure of water in the pipes. Water will therefore not be forced above the valve until the confined air is permitted to escape by the unseating of the device *h*.

d is the neck of the distributor.

e is the enlargement, provided with slits and apertures *ff* for distributing the water in thin sheets.

g is the top disk, in which the device *h* is supported. This disk is screwed into the enlargement *e*.

The modification in Figs. 4 and 5 shows the slots *ff* cut at an angle, so as to spread the water more evenly.

The device *h* is a disk provided at its rear 60 side with a stem, as shown. It may be concaved, convexed, or plain-surfaced on its face; may be secured, by solder fusible at a low temperature, at its face to the stem or inlet *d*, or it may be secured at the stem to the disk *g*. In 65 either case it must be larger than the inlet-openings and arranged to rise only a limited distance, so that it will spread the water in a thin sheet and supply all the outlets with an equal quantity of water.

To prevent the water from entering the distributor in a body, and to cause the same to spread evenly toward all sides and retain the air, as described, is the main object of this invention.

Having thus described my invention, I claim as new and desire to secure by Letters Patent—

1. The combination, with an automatic fire-extinguisher, of a check-valve placed below the automatic distributor, arranged to operate 80 as described.

2. An automatic fire-extinguisher consisting of a distributor provided with holes or slits to discharge the water, and a device for spreading the water, secured by solder fusible at a 85 low temperature, as described.

JOSEPH R. BROWN.
